R. C. STEPHENS.
LIGHTING FIXTURE.
APPLICATION FILED OCT. 11, 1915.

Patented July 15, 1919.
2 SHEETS—SHEET 1.

UNITED STATES PATENT OFFICE.

ROBERT C. STEPHENS, OF ST. LOUIS, MISSOURI.

LIGHTING-FIXTURE.

1,310,149.

Specification of Letters Patent. Patented July 15, 1919.

Application filed October 11, 1915. Serial No. 55,191.

To all whom it may concern:

Be it known that I, ROBERT C. STEPHENS, a citizen of the United States of America, and a resident of the city of St. Louis, State 5 of Missouri, have invented certain new and useful Improvements in Lighting-Fixtures, of which the following is a full, clear, and exact description, reference being had to the accompanying drawings, forming a part of 10 this specification.

My invention relates to lighting fixtures adapted to receive high powered incandescent lamps of the bowl or globe type used at the present time for street and other 15 lighting by electricity.

Many of the fixtures heretofore employed become injuriously hot, and difficult to handle, the insulation of the wires being frequently burned or impaired and the life 20 of the lamp shortened.

One of the objects of my invention is to produce a fixture adapted to use high powered lamps, without becoming extremely hot and without transmitting a high degree of 25 heat to the wires leading to the lamp. I attain this object by a new structure in which the heated air is conducted from the lamp very rapidly. The advantages of such a fixture will be apparent to those skilled in 30 the art.

The value of high powered incandescent lamps is of course due to their high efficiency, but their maximum efficiency is not attained except when the lamp is located in 35 a predetermined position with respect to the lamp-receiving bowl or globe, and to insure the desired efficiency, prior fixtures have usually been designed to receive a particular lamp and bowl or globe. The 40 efficiency of such a fixture is materially decreased by changes in the relative sizes of lamps and bowls or globes. Owing to the lack of interchangeability, the use of such fixtures is limited to the combination of 45 certain bowls or globes and lamps, and while some designed changeability has been attempted, no decided change has been made without affecting the efficiency of the fixture. An object of my invention is to produce 50 a fixture adapted to receive many different kinds of lamps, lamp sockets and bowls or globes, and which is so constructed that the maximum efficiency can be obtained by adjusting the lamp or lamp socket to a predetermined position with respect to the 55 bowls or globes.

With the foregoing and other objects in view the invention comprises the novel construction, combination and arrangement of parts hereinafter more specifically described 60 and illustrated in the accompanying drawings wherein is shown the preferred embodiment of the invention; however, it is to be understood that the invention comprehends changes, variations and modifications which 65 come within the scope of the claims hereunto appended. I use the words "bowl" and "globe" in a broad sense, and not as describing a particular shape of inclosure, 70 as either term is commonly used to describe the same article, owing to the state of the art.

Figure I is a side elevation, partly in section, illustrating a fixture embodying the 75 features of my invention.

Fig. II is a detail view of the adjustable device which supports the lamp.

Fig. III is a fragmentary detail view showing one of the bayonet joints for securing the bowl-supporting ring.

Fig. IV is an enlarged horizontal section taken approximately on the line IV—IV, Fig. I.

Fig. V is a fragmentary horizontal section taken approximately on the line V—V, 85 Fig. I.

The fixture I have shown to illustrate the preferred form of the invention, comprises a tubular hanger A (Fig. I) a hood B screwed onto the lower end of the hanger, 90 a flaring dome C below said hood, a supporting ring D secured to the lower portion of the dome, a ventilator ring E supported by the supporting ring D, and a lamp-receiving bowl or globe F secured to the 95 ventilator ring E. The supporting ring D is provided with an inturned flange 1 forming a seat for the outer marginal portion of the ventilator ring E, and the bowl or globe F is secured to the ventilator ring by 100 means of screws 2. The ventilator ring has a series of openings 3 for the admission of air to the interior of the dome. The supporting ring D, constituting a support for the ventilator ring E, which supports the 105 bowl or globe F, is provided with a series of bayonet slots 4 (Figs. I and III) each having a recess 5 at its inner end. The dome is provided with supporting pins 6 adapted to lie in the recess 5 to secure the 110 ring D. The supporting ring D is positively prevented from turning by means of

locking screws 7 adjustably fitted to the dome and adapted to extend into the vertical portions of the bayonet slots 4. Since these screws 7 prevent the supporting ring 5 D from turning independently of the dome C, they also prevent said parts from being separated from each other. In removing the bowl or globe from the dome, the locking screws 7 are adjusted to withdraw their 10 inner ends from the bayonet slots; the supporting ring D is then turned and moved downwardly to release it from the supporting pins 6.

When the parts are assembled, the ventilator ring E, which supports the bowl or globe is firmly secured to the supporting ring D by means of a series of adjustable clips 8 arranged in a plane above the ventilator ring E and adjustably secured to the 15 supporting ring D to prevent the ring E from moving upwardly; each clip having a vertical slot 9 for the reception of a screw 10, the latter being screwed into the supporting ring D. Before applying the supporting ring D to the dome C, the retaining clips are adjusted to properly engage the ventilator ring E and are then locked by the screws 10, thus firmly securing the bowl F and ventilator ring E to the supporting 20 ring D.

12 designates an incandescent electric lamp, arranged within the bowl or globe F and fitted to a socket 13, the latter having an extension 13' screwed onto the lower end of 25 a sleeve K. The upper end of the sleeve K is screwed into the upper portion of the dome C. The sleeve K, through the extension 13', constitutes an adjustable support for the socket 13 and lamp 12, and may be 30 rotated to adjust the vertical position of the lamp with respect to the bowl or globe F. As previously stated, the maximum lighting efficiency is obtained by locating the lamp in a predetermined position with respect to 35 the bowl or globe F, and to insure this efficiency, lighting fixtures have been constructed to hold a predetermined size of lamp and bowl or globe in fixed relative positions. Hence, the efficiency of the prior 40 devices may be greatly reduced by substituting one lamp for another, or by the use of a bowl or globe not adapted to coöperate with the lamp for which the fixture was designed. My improved lighting fixture is 45 adapted to receive lamps and bowls or globes of various different styles and dimensions; and the maximum lighting efficiency can be obtained by rotating the supporting sleeve K to vertically adjust the lamp to a point 50 where it will coöperate with the bowl or globe to produce the desired lighting effect. To aid the operator in the determination 55 of the exact position of the lamp, the threaded upper portion of the sleeve K (Figs. I and II) is provided with a series of

depressions 15 for the reception of a locking screw 16. The fixture is particularly intended to receive certain frequently used combinations of lamps and bowls or globes, and when it is to be used with one of the 70 predetermined combinations, the supporting sleeve K will be adjusted to locate one of its depressions 15 at a point opposite the screw 16. Obviously, the parts may thus be easily and accurately adjusted to the predetermined positions, to insure the maximum lighting efficiency, irrespective of the dimensions or shape of the lamp and bowl or globe. 75

To prevent the fixture from becoming extremely hot when subjected to the action of a large incandescent lamp, the flaring dome C is provided with a series of upwardly extending radiating fins 17 forming passageways for deflecting air currents along the 80 outer face of the dome and to the upper portion thereof. The heat generated by the lamp, is transmitted through the dome, to the radiating fins 17 which assist in removing heat from the outer face of the dome. 90 The temperature of the dome is reduced by transmitting some of its heat to the radiating fins 17, and also by the air currents which are guided along the outer face of the dome by the radiating fins. Webs 17', forming upwardly extending continuations of some of the fins 17, are formed integrally with a securing member 20 and a ventilating ring 21 surrounding the webs 17' and spaced from the flaring dome C and fins 17 so that 100 the upper portion of the dome is open, as shown in Fig. I, that air currents flowing upwardly along the radiating fins 17, will pass through the ventilating ring 21 into the hood B and escape under the rim of the hood B. 105 The air flowing upwardly through the interior of the dome will also pass into the hood B and escape under the rim of the hood B. When the fixture is in service the dome is constantly subjected to the action of air currents flowing through passageways formed by radiating fins 17, so that the dome will 110 withstand the action of the lamp without becoming extremely hot, and without transmitting a high degree of heat to the insulation of the wires (not shown). The wires may be inserted through the tubular hanger A, or through openings 23 in the ventilating ring 21. 115

To prevent the transmission of heat from the dome C to the hanger A, the dome C and hood B are insulated from each other by a suitable non-conductor of heat 24 as asbestos. This insulating material lies between and is fitted to the hood B and dome 125 C, said parts being fastened together by screws 25.

I claim:—

1. In a lighting fixture, the combination of a lamp-receiving globe, and a dome above 130

said globe; said dome being provided with a series of radiating fins and having at its upper end a ventilating ring spaced from the main body of the dome, some of said radiating fins serving to connect said ring and dome.

2. In a lighting fixture, the combination of a lamp-receiving globe, a dome above said globe, and a hood above said dome; said dome being provided with a series of radiating fins and including a ventilating ring connected to the body of the globe by some of said fins, said ventilating ring being spaced from the body of said dome to provide air passageways leading to said hood.

3. In a lighting fixture, a lamp-receiving globe, a dome above said globe, said dome being provided with a series of radiating fins for conducting heat from its body portion and said radiating fins being arranged to form passageways for deflecting air currents along the outer face of said dome and to the upper portion thereof, the upper portion of said dome having an opening which communicates with its interior and also with the passageways formed by said radiating fins, and a hood above said opening.

4. In a lighting fixture, a lamp-receiving globe, a dome above said globe, said dome being provided with a series of radiating fins forming passageways for deflecting air currents along the outer face of the dome and to the upper portion thereof, the upper portion of said dome being in open communication with said passageways and also with the interior of the dome, a ventilating ring being formed around the upper portion of said dome, and a hood above said dome adapted to receive the air flowing from the upper portion of the dome.

5. In a lighting fixture, a lamp-receiving globe, a flaring dome above said globe, a lamp support at the upper end of said dome and an opening being formed between said lamp support and the side wall of said dome, a ventilating ring surrounding said opening, the outer face of said dome being provided with a series of radiating fins forming pas-

sageways for the deflecting air currents to a point within said ventilating ring, and a hood above said dome.

6. In a lighting fixture, a dome, a lamp-receiving globe, a ventilator ring surrounding said globe at a point near the lower portion of the dome, said ventilator ring having openings for the admission of air to the interior of said dome, the outer face of said dome being provided with radiating fins forming passageways for conducting air to the upper portion of the dome, the upper portion of said dome being open to permit the discharge of air from the interior of the dome.

7. In a lighting fixture, a lamp-receiving globe, a supporting ring forming a seat for the upper portion of said globe, said supporting ring being provided with bayonet slots, a supporting device including pins arranged in said bayonet slots, and means for locking said supporting ring to prevent it from turning independently of said supporting device, said means including pins adjustably secured to the supporting device and adapted to extend into said bayonet slots.

8. In a lighting fixture, the combination of a dome, a supporting ring detachably secured to said dome, and having an inturned flange, a ventilator ring seated on said flange, and a lamp-receiving globe secured to said ventilator ring.

9. In a lighting fixture the combination of a supporting device having an inturned flange, a globe-supporting member seated on the flange, and a vertically adjustable stop secured to the body of the supporting device and adapted to control the movement of the globe-supporting member.

10. In a lighting fixture the combination of a supporting device having an inturned flange, a globe-supporting member seated on the flange, and a vertically adjustable stop, comprising a retaining clip and a tightening screw passing through the clip into the supporting device.

ROBERT C. STEPHENS.
